UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A. CORPORATION.

CLOCK.

1,037,527.

Specification of Letters Patent. Patented Sept. 3, 1912.

Application filed June 10, 1912. Serial No. 702,750.

To all whom it may concern:

Be it known that I, WILSON E. PORTER, a citizen of the United States, residing at New Haven, in the county of New Haven and State of Connecticut, have invented a new and useful Improvement in Clocks; and I do hereby declare the following, when taken in connection with the accompanying drawings and the characters of reference marked thereon, to be a full, clear, and exact description of the same, and which said drawings constitute part of this application, and represent, in—

Figure 1 a view in front elevation of a clock constructed in accordance with my invention. Fig. 2 a view in front elevation of the clock-movement as it appears when removed from the case, and drawn on an enlarged scale. In this view the rack is shown in its normal position. Fig. 3 a corresponding view showing the rack dropped ready for the clock to begin to strike eleven p. m., and the lifting-lever just about to drop off the nose of the cam. Fig. 4 a broken view of the movement in front elevation with the dial-work removed, and with the remaining parts corresponding in position to their positions in Fig. 2. Fig. 5 a similar view with the parts corresponding in position to their positions in Fig. 3. Fig. 6 a detached view in front elevation of the warn-lever and lifting-lever which act as one piece. Fig. 7 a plan view thereof. Fig. 8 a detached perspective view of the stop-lever. Fig. 9 a plan view of the rack and its rack-arm.

My invention relates to an improvement in that class of clocks known to the trade as "Elk" clocks, for the reason that they are constructed with special reference to striking only once in twenty-four hours, and that at eleven p. m., the object being to provide at a low cost a simple, durable and reliable clock of the character described.

With these ends in view, my invention consists in an "Elk" clock having certain details of construction and combinations of parts as will be hereinafter described and pointed out in the claim.

In carrying out my invention as herein shown, I employ a twenty-four hour wheel 2 which is mounted upon a stud 3 riveted so as to project from the outer face of the front movement-plate 4 of the clock, the said wheel being furnished with a twenty-four hour cam 5, and held in place by a screw 6 enter-

ing the stud 3 which is threaded for the purpose. The said wheel 2 is meshed into and driven by a special twelve-hour wheel 7 mounted upon an hour-hand socket 8 which carries an hour-wheel 9 meshed into and driven by a dial-pinion 10 on a dial-wheel 11 which is driven by a cannon-pinion 12, the parts described being of ordinary construction and arrangement except the twenty-four hour wheel 2, the twenty-four hour cam 5 and the special twelve-hour wheel 7.

Riding upon the edge of the twenty-four hour cam 5 is a flexible lifting-arm 13 having its extreme outer end bent inward at a right angle and beveled so as to permit the wheel 2 and cam 5 to be "turned back" in setting the clock without deranging the strike mechanism. The said arm 13 is rigidly secured to the outer end of the hub 14 of a warn-lever 15 arranged horizontally in front of the said front movement-plate 4, and swinging upon a stud 16 mounted therein. A spring 17 coiled upon the hub 14 and respectively attached at its ends to the warn-lever 15, and the plate 4, exerts a constant effort to swing the said finger 13 and lever 15 from left to right downward.

At its right hand end the warn-lever 15 is turned inward to form a warn-finger 18 extending through a clearance-opening 4^a in the front movement-plate 4 and co-acting with a warn-pin 19 mounted in the warn-pin wheel 20 of the strike-train. At its right hand end the said warn-lever 15 is also formed with a depending arm 21 bent forward at its lower end to form a lifting-finger 22 which co-acts with a bevel 23 upon the lower edge of a stop-lever 24 pivotally hung by its lower end upon a stud 25 in the plate 4, a helical spring 26 being provided for exerting a constant effort to swing the said lever 24 from right to left. At its upper end, the stop-lever 24 is formed with a stop-finger 27 extending inward through the said clearance opening 4^a into position to engage with the warn-pin 19 carried by the warn-wheel 20. The said stop-lever 24 is also provided with a rack-retaining pin 28 which co-acts with the teeth of a segmental rack 29 which is lifted step-by-step in the usual manner of such mechanisms by a gathering-pin 30 mounted in a gathering-hub 31 located upon the projecting forward end of the gather-

ing-pin arbor 32 of the strike-train. The said rack 29 is located at the outer end of a rack-arm 33 hung upon a stud 34 mounted in the front movement-plate 4, the said 5 rack-arm 33 being furnished with a spring 36 exerting a constant effort to swing the rack downward. A rack-stop pin 37 is located in the front movement-plate 4 in position to be engaged by the lower end of the 10 rack 29 when the same is dropped sufficiently to bring into action eleven of the teeth on the rack 29 so that the clock will strike eleven at eleven o'clock in the evening. As shown, though this is not necessary, the clock is provided with a repeating 15 plunger 38 mounted in brackets 39 and engaging at its lower end with an operating-pin 40 carried by the outer end of the warn-lever 15, so that when the plunger is depressed against the tension of its spring 41, the rack will be allowed to fall and the strike mechanism let off in the usual manner of repeating clocks.

As already explained, my improved clock 25 is designed to strike eleven at eleven o'clock in the evening and at no other time during the twenty-four hours of the day. Normally the stop-pin 19 in the stop-pin wheel 20 is engaged with the upper face of the 30 stop-finger 27 of the stop-lever 24. However, as eleven o'clock p. m. approaches, the cam 5 raises the lifting-lever 13 and hence the warn-lever 15, the lifting-finger 22 of which engages with the beveled edge 23 of 35 the stop lever 14 and swings the same from left to right, whereby the stop-finger 27 of the stop-lever 14 and swings the same from out from under the pin 19, thus allowing the stop-pin wheel 20 to move far enough 40 to engage the stop-pin 19 with the inner face of the warn-finger 18 of the warn-lever 15. In common parlance the clock is now "on the warn" and ready to strike. At about this time, the rack-retaining pin 28 45 is moved by the swinging of the lever 24 from left to right out of engagement with the teeth of the rack 29 which immediately falls or swings downward under the influence of the rack-spring 36 until it is stopped 50 by the engagement of its lower end with the rack-stop pin 37. This downward movement of the rack may take place before or after the clock is warned, this being immaterial and depending upon the 55 way in which the clock is timed as to warning and the dropping of the rack. Just at eleven o'clock, the end of the lifting-lever

12 drops off the high point of the cam 5 and permits the warn-lever 15 to fall, whereby its finger 18 will be carried below the range 60 of the stop-pin 19, leaving the strike-train free to start the revolution of the gathering hub 31, the gathering pin 30 of which will now lift the rack step-by-step as the clock strikes from 1 to 11, the stop-lever 24 being all this time prevented from swinging from right to left sufficiently to bring its finger 27 under the pin 19, by the engagement of the rack-retaining pin 28 with those portions of the rack lying between the teeth 65 thereof. As the clock strikes eleven, the pin 28 moves under the lower end of the rack as shown in Fig. 4, permitting the stop-lever 24 to be swung sufficiently from left to right to bring its finger 27 into the 70 path of the pin 19 which engages with it and stops the strike-train. At the end of the striking operation, the clock may be said to have returned to its normal position in which it remains say from twenty-three 75 hours or more, when the cycle of operations above detailed will be repeated.

I claim:—

In a clock striking once in twenty-four hours, the combination with a twenty-four 85 hour wheel, of a twenty-four hour cam carried thereby, means for rotating the said wheel and cam once in twenty-four hours, a lifting lever engaging with the said cam, a warn-lever mounted with the said lifting-lever and operated thereby, and provided with a warn-finger and a lifting finger, a stop-pin wheel carrying a stop-pin co-acting with the warn-finger of the warn-lever, 90 a pivotal stop-lever provided with a stop-finger co-acting with the said stop-pin, with a rack-retaining pin and adapted to be operated by the lifting-finger of the warn-lever, a rack the teeth of which co-act with the said rack-retaining pin, a gathering 95 hub, a gathering-pin co-acting with the rack, and a rack-stop pin located in position to arrest the falling of the rack when a pre-determined number of rack teeth have been presented to the action of the gathering- 100 pin.

In testimony whereof, I have signed this specification in the presence of two subscribing witnesses.

WILSON E. PORTER.
